UNITED STATES PATENT OFFICE.

WALTER FRANCIS KEENAN, JR., OF PELHAM, NEW YORK, ASSIGNOR TO POWER SPECIALTY COMPANY, OF NEW YORK, N. Y., A CORPORATION OF NEW YORK.

SUPERHEATER BOILER.

Application filed April 17, 1925. Serial No. 23,783.

The general object of the present invention is to provide a boiler of the vertical water tube type with improved steam superheating provisions.

More specifically, the object of the invention is to provide an effective combination of a superheater with a waste heat boiler of the well known Wickes type, whereby a desirably high superheating effect may be obtained, with a superheater which is simple in construction and arrangement, and is so disposed as to facilitate inspection and repairs, and which does not weaken, or tend to produce air leakage through, the boiler shell, or require any change in its cylindrical section.

The various features of novelty which characterize my invention are pointed out with particularity in the claims annexed to and forming a part of this specification; but for a better understanding of the invention, however, its advantages and specific objects attained with its use, reference should be had to the accompanying drawings and descriptive matter in which I have illustrated and described the best forms of my invention.

Of the drawings:

Fig. 1 is a vertical section on the line 1—1 of Fig. 3;

Fig. 2 is an elevation of the lower portion of the boiler taken at right angles to Fig. 1;

Fig. 3 is a plan section on the line 3—3 of Fig. 1;

Fig. 4 is a partial section taken similarly to Fig. 3, but on a larger scale;

Fig. 5 is an elevation of a portion of the boiler; and

Fig. 6 is a section on the line 6—6 of Fig. 4.

The drawings show a waste boiler of the well known Wickes type, comprising an upper steam and water drum A, a lower water drum B, and vertical water tubes C connecting said drums and enclosed within a cylindrical boiler shell formed by an outer metal casing D and a refractory lining d. The heating gases enter the boiler shell through an inlet D' and pass out through an outlet D² at the top of the intertube space and at opposite sides of a central baffle E which extends from the drum A downward terminating sufficiently far above the bottom drum B to provide space for the gases to sweep around the lower end of the baffle.

In accordance with the present invention,

some of the water tubes C are omitted to provide space for one or more vertical rows of horizontal superheater elements F parallel to and in proximity to the baffle E, and preferably at the front or high temperature side of the latter. In the particular form of construction shown the third row of water tubes C in front of the baffle is replaced by a single row of superheater elements F. The vertical row of elements F extends throughout substantially the entire distance between the drums A and B. The elements F are of the Foster type, comprising tubes f enclosed in externally corrugated tubular cast iron casings. The bare ends of the tubes f extend through the boiler shell and have their ends projecting out from the casing D. One end of each tube f is connected by an elbow f' and short transverse pipe f² to the superheater inlet header H which is supported in a vertical position by means of brackets H' secured to the exterior of the boiler shell D, and which receives steam by suitable pipe connections (not shown) from the steam drum A. The opposite end of each tube f is connected directly to the superheater outlet header J also supported in a vertical position by brackets J' secured to the boiler shell D. The header H is shown as provided with a drainage connection H². At one side of the boiler the boiler shell is formed with holes just large enough to receive the tubes f and the latter are advantageously expanded into holes in a reinforcing plate or pad F² secured against the outer side of the casing, thus making the joints tight against air leakage notwithstanding the substantial difference in the pressures within and without the boiler shell which may amount to four or five pounds. The ends of the tubes f may be rolled or otherwise secured in the header J.

At the opposite side of the boiler openings are formed in the boiler shell large enough to permit the passage of the encased portions of the elements F, for removal and replacement if necessary. The portions d' of these openings which are formed in the refractory portion d of the shell are rectangular and normally contain sil-o-cel or the like packed about the tubes f. At the outer ends of the holes d² the casing D is formed with a vertical slot D³, the edges of which are secured to stiffening angle bars D⁴. This slot is closed by a series of plates F⁵, one for each

tube *f*, each of the latter passing through and being expanded into the corresponding plate *F*⁵. The plates *F*⁵ are bolted to the stiffening angles *D*⁴, and gas tight joints between the plates *F*⁵ and the boiler shell *D* are obtained by means of gaskets *F*⁶. Advantageously the superheater elements *F* are supported between their ends by supports *G*. These are shown as consisting of vertical cast iron plate-like bodies formed with holes receiving the elements *F*, and with flanges or lugs *G*' engaging the water tubes and preventing horizontal displacement toward or away from the baffle *E*.

15 With the described arrangement, it is possible to obtain a relatively high superheating effect with a relatively small amount of superheating surface, and the water tubes omitted to make room for the superheater 20 form but a relatively small portion of the boiler heating surface. The use of the invention requires no change in the general design of the boiler. The tightness of the boiler shell is maintained while the superheater elements may be replaced without 25 great difficulty. The arrangement of the superheater inlet and outlet header *H* and *J*, at opposite sides of the boiler, permits of very simple and direct steam pipe connections 30 to the headers.

While in accordance with the provisions of the statutes, I have illustrated and described the best embodiments of my invention now known to me, it will be apparent 35 to those skilled in the art that changes may be made in the form of the apparatus disclosed without departing from the spirit of my invention as set forth in the appended claims, and that in some cases certain features 40 of my invention may be used to advantage without a corresponding use of other features.

Having now described my invention, what I claim as new and desire to secure by Letters Patent, is:

1. The combination with a boiler comprising a vertical shell and vertical water tubes and a centrally disposed baffle providing up and down heating gas passes, of a vertical 50 row of horizontal superheater elements parallel to and alongside said baffle and having their ends extending through said shell and vertical inlet and outlet headers external to said shell and to which the opposite 55 ends of said elements are connected.

2. The combination of claim 1, and in conjunction therewith a superimposed set of vertically disposed plate-like bodies formed with apertures receiving intermediate portions of said superheater elements which are thereby supported.

3. The combination of claim 1, and in conjunction therewith a superimposed set of vertically disposed plate-like bodies formed 65 with apertures receiving intermediate por-

tions of said superheater elements which are thereby supported, said bodies having their ends received between adjacent pairs of water tubes and being provided with transverse water tube engaging portions whereby 76 said bodies are held against displacement.

4. The combination with a boiler having vertical water tubes and a vertical enclosing shell comprising an outer metallic casing and an inner refractory lining, of a superheater 75 consisting of horizontal tubes extending across the boiler between groups of water tubes and having end portions passing through the shell at opposite sides of the boiler and ribbed casings surrounding the 80 portion of the tubes within the shell, the latter being formed with openings at one side large enough to permit the passage of the encased portions of the superheater elements, and sectional metallic plates uniting with the casing to seal said opening and formed with apertures through which the corresponding ends of the elements extend and in which they fit tightly.

5. The combination with a vertical water 90 tube boiler having a cylindrical shell comprising an outer metal casing which is formed with a vertical slot at one side and at the other side with a vertical series of holes, of a superheater including a vertical 95 row of horizontal tubes extending across said shell and having their ends at one side of the boiler passing through and snugly fitting in said holes, and plates bridging said slot and formed with holes snugly receiving 100 the corresponding ends of said tubes, said tubes being surrounded within the casing by ribbed tube casings, and said slot being wide enough to permit the passage of the encased portions of the tube when said plates are 105 removed.

6. The combination with a vertical water tube boiler having a cylindrical shell comprising an outer casing which is formed with a vertical slot at one side and at the 110 other side with a vertical series of holes, of angle bars reinforcing said casing at the edges of said slot, a superheater comprising a vertical row of horizontal tubes extending across said shell and having their ends at 115 one side of the boiler passing through and snugly fitting in said holes, plates bridging said slot and removably secured to said bars and formed with holes snugly receiving the corresponding ends of said tubes, said tubes 120 being surrounded within the casing by ribbed tube casings and said slot being wide enough to permit the passage of the encased portions of the tube when said plates are removed.

Signed at New York city, in the county of New York, and State of New York, this 125 14th day of April, A. D. 1925.

WALTER FRANCIS KEENAN, JR.
